UNITED STATES PATENT OFFICE

164,120

ASH TRAY

Victor J. Mahony, North Hollywood, Calif.

Application July 8, 1950, Serial No. 11,025

Term of patent 7 years

(Cl. D85—2)

To all whom it may concern:

Be it known that I, Victor J. Mahony, a citizen of the United States, residing in North Hollywood, in the county of Los Angeles and State of California, have invented a new, original, and ornamental Design for an Ash Tray, of which the following is a specification, reference being had to the accompanying drawing, forming part thereof.

Fig. 1 is a perspective view of an ash tray, showing my new design.

Fig. 2 is a partial elevational and partial sectional view thereof.

I claim:

The ornamental design for an ash tray, substantially as shown.

VICTOR J. MAHONY.
